US00D904406S

(12) **United States Design Patent** (10) **Patent No.:** **US D904,406 S**
Wei et al. (45) **Date of Patent:** **** Dec. 8, 2020**

(54) **REMOTE CONTROLLER**

(71) Applicant: **HTC Corporation**, Taoyuan (TW)

(72) Inventors: **Chang-Hua Wei**, Taoyuan (TW);
Shih-Hsiu Lee, Taoyuan (TW)

(73) Assignee: **HTC Corporation**, Taoyuan (TW)

(**) Term: **15 Years**

(21) Appl. No.: **29/731,778**

(22) Filed: **Apr. 17, 2020**

Related U.S. Application Data

(62) Division of application No. 29/712,359, filed on Nov. 7, 2019, which is a division of application No. 29/660,941, filed on Aug. 23, 2018, now Pat. No. Des. 885,386.

(57) **CLAIM**

The ornamental design for a remote controller, as shown and described.

DESCRIPTION

FIG. 1 is a front perspective view of a remote controller in accordance with our new design;

FIG. 2 is a front view thereof;

FIG. 3 is a rear view thereof;

FIG. 4 is a left view thereof;

FIG. 5 is a right view thereof;

FIG. 6 is a top plan view thereof;

FIG. 7 is a bottom plan view thereof; and,

FIG. 8 is a rear perspective view thereof.

The broken lines immediately adjacent the claimed areas represent the bounds of the claimed design while all other broken lines are directed to environment and are for illustrative purposes only and form no part of the claimed design.

1 Claim, 7 Drawing Sheets
